UNITED STATES PATENT OFFICE.

GEORGE R. WEBBER, OF AUGUSTA, MAINE.

DESIGN FOR A DISPLAY CONTAINER OR SIMILAR ARTICLE.

Application filed March 17, 1928. Serial No. 25,899. Term of patent 14 years.

To all whom it may concern:

Be it known that I, GEORGE R. WEBBER, a citizen of the United States, residing at Augusta, county of Kennebec, State of Maine, have invented a new, original, and ornamental Design for a Display Container or Similar Article, of which the following is a specification, reference being had to the accompanying drawing, forming part thereof. The single figure of the drawing is a side elevation of a display container or similar article showing my new design.

I claim:

The ornamental design for a display container or similar article, as shown.

GEORGE R. WEBBER.
